UNITED STATES PATENT OFFICE.

WILLDE A. INGALLS, OF RICHMOND, VIRGINIA.

ROADSIDE SIGNAL.

Application filed October 10, 1925. Serial No. 61,692.

This invention is a roadside signal device of the type used to impart warnings as to traffic or to indicate road conditions.

One of the objects of the invention is to provide a signal device of the character mentioned which will be simple in construction, but capable of withstanding to a maximum degree, deterioration under exposure to the action of the elements and such attempts at destruction as may be due to vandalism. A further object is to provide a signal device equipped with a normally unbreakable light reflecting surface, means for coloring a beam of light reflected therefrom, and means for affording maximum protection for said surface. A further object is to provide simple means for focusing the device.

The invention will be hereinafter fully set forth and particularly pointed out in the claims.

In the accompanying drawings:-

Figure 1 is a front elevation illustrating a signal device constructed in accordance with the invention. Figure 2 is a side elevation thereof. Figure 3 is a transverse sectional view on the line 3-3, Figure 2. Figure 4 is a detail sectional view illustrating means for changing the focus of the reflector. Figure 5 is a perspective view illustrating one of the supporting devices. Figure 6 is a detail view illustrating a modification of the protector frame.

Referring to the drawing, 10 designates a back plate of any desired size and shape, 35 to which is secured a protector frame 11. The frame 11 is preferably constructed with a base flange 12 and an overhanging top flange 13, bolts 14 being shown as passed through the base flange and the back plate 40 to secure the frame in place.

The light reflecting element comprises a metal sheet 15, having one surface polished to provide a reflector, said polished surface being covered by a sheet 16 of transparent colored material. The sheets 15 and 16 are bound together at their edges by suitable binding strips 17, as shown, so that the back surface of said color screen will be in contact throughout its area with a corresponding

area of the front surface of the reflector 50 member. Any desired contour may be imparted to the surface of sheet 15, but for purposes of illustration it is shown slightly concaved.

For the purpose of the invention it is preferred to construct sheet 16 of a material which will not easily fracture under shocks, such as some of the forms of cellulose materials now on the market. The light-reflecting element is held in place by the lower 60 flanges 18 of anchoring devices 19, which are removably secured to the body of frame 11, by means of bolts 20.

Interposed between the top flange 13 of the frame 11, and the contiguous top flanges 65 21 of the anchor members, and retained in place by them, is a wire mesh protector screen 22. Said screen is of sufficiently heavy mesh to resist the blows of large stones and other missiles which may be projected 70 against it, and is also spaced far enough from the reflector member to protect the latter from injury or defacement by vandals.

It is sometimes desirable to change the angle of a portion of the reflector member 75 with respect to the back plate 10. Such adjustment may be accomplished by means of the arrangement shown in Figure 4. Referring to said figure, 23, designates an adjusting screw, mounted in the back plate 10, 80 and bearing against the underside of the sheet 15 near the edge thereof. It is obvious from the drawing that the angle is varied by adjusting the screw 23, the reflector member being sufficiently resilient to 85 yield when pressure is applied thereto. When the adjusting device of Figure 4 is used, the anchor devices 19^a are made in two parts as shown, so that the position of the lower flange may be changed to conform 90 to the adjustment of said reflector members.

The signal device may be supported in any desired manner. It is preferred, however, to provide the back plate 10 with lugs 95 24, each provided with a slot 25. Complementary to said lugs are support straps having loop portions 26 shaped to embrace a post 27, and having arms 28 which overlap

the lugs. The loop portions 26 are tightened or loosened by means of bolts 29, and the arms 28 are connected to the lugs 24 by means of bolts 30 which pass through 5 the slots 25. If desired suitable signs 31 may be attached to the device as shown.

In practice, the screen 22 is secured beneath the flange 13 of the frame 11, by means of the anchor devices 19, so that the 10 frame 11 and the screen 22 become a unitary structure. The reflector member is then placed on the back plate 10, and frame 11 placed over it and secured in position with the lower flanges of the anchor devices 15 clamping the reflector member in place.

In attaching the signal to a post, the bolts 29 are loosened to permit the loops to pass around the post, after which the loops are tightened to clamp the said post. The 20 arms 28 are then connected with the lugs 24 by means of the bolts 30. To focus the sign, any desired radial position with respect to the post, is obtained by loosening the loops 26 and then turning the support straps 25 to the desired angle, after which the loops are again tightened. The vertical angle may be varied by loosening the bolts 30 and tilting the signal member, the slots 25 and the arms 28 serving to permit this adjustment. 30 If any finer adjustment of focus is required it may be effected by means of the screw 23.

In lieu of making the protector frame of a single piece of metal as shown in Figures 1, 2 and 3, it may be desirable to make it of 35 a plurality of parts as illustrated in Figure 6, in which the parts of the frame are shown as provided with a joint 30. In this form of the invention the anchor members 31 perform the additional function of reinforcing or splicing said joint.

The advantages of the invention will be readily apparent to those skilled in the art to which it belongs. For instance, it will be noted that by constructing the reflector of 45 metal it may not be broken, and therefore will withstand shocks which would be fatal to glass. Neither will it readily deteriorate under the action of the elements. By employing a transparent color screen, the reflecting qualities of the metal sheet 15 are not in the least impaired, and it is possible to impart any desired color which may be considered suitable for signal purposes. An important advantage of this arrangement is 50 that at night, the beam of light projected from an automobile headlight, will be reflected back in such a manner as to give the effect of a colored beam of light projected toward the driver, and thus promptly warn 55 him of the position of the signal. The means by which the device may be focused insures a maximum of efficiency in the performance of this reflecting function. By adding the heavy protective wire screen, the

reflector may not be readily damaged and is 65 not readily open to injury by vandals or missiles. It will be particularly noted that the signal is very simple in construction, can be manufactured at small cost, and is of a character which may be equally useful in 70 congested areas as well as in the less settled districts.

Having thus explained the nature of the invention and described an operative manner of constructing and using the same, although without attempting to set forth all 75 of the forms in which it may be made, or all of the forms of its use, what is claimed is:—

1. A signal device of the character described comprising a supporting plate, a reflector member bearing against one face of said plate, a protector frame having a portion surrounding the periphery of said reflector member, clamping means located within said protector frame and cooperating 80 with said supporting plate to retain said reflector member in place, and means for securing said protector frame to said supporting plate.

2. A signal device of the character described comprising a supporting plate, a metal reflector sheet, a transparent cover for said reflector sheet, means for binding the edges of said sheets together to produce a unitary reflector member, a protector frame 95 having a portion surrounding the periphery of said reflector member, clamp means within said protector frame and cooperating with said supporting plate to retain the protector frame in place, and means for securing said 100 protector frame to said supporting plate.

3. A signal device of the character described comprising a supporting plate, a reflector member bearing against one face of said plate, a protector frame having a portion 105 surrounding the periphery of said reflector member, anchor members secured to the interior of said protector frame and cooperating with the supporting plate to clamp said reflector member in place, and means for securing said protector frame to said supporting plate.

4. A signal device of the character described comprising a supporting plate, a reflector member bearing against one face of said plate, a protector frame having a portion 115 surrounding the periphery of said reflector member, anchor members secured to the interior of said protector frame and cooperating with the supporting plate to clamp said 120 reflector member in place, means for securing said protector frame to said supporting plate, and a protecting screen also retained in position by said anchor members.

5. A signal device of the character described comprising a supporting plate, a reflector member resting thereon, a protector frame secured to said support and having a portion 125

- surrounding the periphery of said reflector member, said frame having a flange overhanging and spaced from said reflector member, a protector screen extending over said reflector member and having its edges projecting beneath said flange, and means cooperating with the flange to retain said protector screen in place. 65
- 5 6. A signal of the character described comprising a supporting plate, a reflector member resting thereon, a protector frame secured to said plate and having a portion surrounding the periphery of said reflector member, said frame having a flange overhanging and spaced from said reflector member, a protector screen extending over said reflector member and having its edges projecting beneath said flange, and an anchor member carried by said frame and cooperating with said flange to engage the edges of said screen. 70
- 10 7. A signal of the character described comprising a supporting plate, a reflector member resting thereon, a protector frame secured to said plate and having a portion surrounding the periphery of said reflector member, said frame having a flange overhanging and spaced from said reflector member, a protector screen extending over said reflector member and having its edges projecting beneath said flange, and an anchor member carried by said frame and cooperating with said flange to engage the edges of said screen, said anchor member also cooperating with said supporting plate to retain said reflector member in place. 75
- 15 8. A signal device of the character described comprising a supporting plate, a reflector member resting thereon, a protector frame secured to said plate and having a portion surrounding the periphery of said reflector member, said frame having a flange overhanging and spaced from said reflector member, a protector screen extending over said reflector member and having its edges projecting beneath said flange, one or more anchor members carried within said frame and each provided with inwardly extended spaced apart flanges, one set of flanges cooperating with said supporting plate to retain said reflector member in place, and a protector screen clamped between the other set of anchor member flanges and the overhanging flange of the protector frame. 80
- 20 9. A signal device of the character described comprising a supporting plate, a reflector member resting upon said plate, a protector frame having a portion surrounding the periphery of said reflector member, means for securing the protector frame to said supporting plate, means carried by said protector frame and cooperating with the supporting plate to retain the reflector member in place, and means for changing the angular disposition of the reflector member with respect to the surface of the supporting plate. 85
- 25 10. A signal device of the character described comprising a supporting plate, a reflector member resting against said supporting plate, a protector frame engaging said supporting plate and having means for retaining said reflector member in place, and an adjusting member engaging said reflector member so as to move it toward and from said supporting plate. 90
- 30 11. A signal device of the character described comprising a supporting plate, a reflector member resting upon and covering the front face of said plate, a protector frame having a portion enclosing the periphery of said reflector member and having internal means cooperating with said plate to retain said reflector member in place, support lugs secured to the back face of said supporting plate, and post-engaging members adjustably connecting with said lugs. 95
- 35 12. A signal device of the character described comprising a supporting plate, a reflector member resting upon and covering the front face of said plate, a protector frame having a portion enclosing the periphery of said reflector member and having internal means cooperating with said plate to retain said reflector member in place, slotted supporting lugs secured to the back face of said plate, support devices provided with arms, and bolts extending through the slots of said lugs and engaging said arms. 100
- 40 13. A signal device of the character described comprising a supporting plate, a reflector member resting upon and covering the front face of said plate, a protector frame having a portion enclosing the periphery of said reflector member and having internal means cooperating with said plate to retain said reflector member in place, support lugs secured to the back face of said supporting plate, post-engaging members adjustably connected with said lugs, and means whereby the radial positions of said post-engaging members may be varied with respect to the post. 105
- 45 14. A signal device of the character described comprising a supporting plate, a reflector member resting upon and covering the front face of said plate, a protector frame having a portion enclosing the periphery of said reflector member and having internal means cooperating with said plate to retain said reflector member in place, slotted supporting lugs secured to the back face of said plate, support devices provided with arms, bolts extending through the slots of said lugs and engaging said arms, said post-engaging members having means whereby their radial positions on a post may be varied. 110
- 50 120
- 55 125

15. A signal device of the character described comprising a sheet metal reflector member, having a polished reflector surface, a sheet-like color screen of transparent non-vitreous material covering said reflector member, the back surface of said color screen being in contact throughout its area with a corresponding area of the polished

reflector surface of the said sheet metal member, and a protecting cover for said reflector member and said color screen, said cover having openings therein through which a beam of light may be reflected. ¹⁰

In testimony whereof I have hereunto set my hand.
